Primary Examiner — Michael Pratt

(74) Attorney, Agent, or Firm — Wolf, Greenfield & Sacks, P.C.

(57) **CLAIM**

The ornamental design for a clipboard, as shown and described.

DESCRIPTION

FIG. 1 is a front elevational view of the clipboard;
 FIG. 2 is a detailed front elevational view of the clipboard taken along line 2 shown in FIG. 1;
 FIG. 3 is a left side elevational view of the clipboard of FIG. 2, the right side elevational view being a mirror image thereof;
 FIG. 4 is a top plan view of the clipboard of FIG. 2;
 FIG. 5 is a bottom plan view of the clipboard of FIG. 2; and,
 FIG. 6 is a bottom front right perspective view of the clipboard of FIG. 2.
 The broken lines in the figure drawings represent environmental structure and form no part of the claimed design.
